Primary Examiner — Khawaja Anwar*Assistant Examiner* — Julice Seung Eun Oum(74) *Attorney, Agent, or Firm* — Emerson, Thomson & Bennett, LLC; Roger D. Emerson; Peter R. Detorre(57) **CLAIM**

The ornamental design for a ski exercising apparatus, as shown and described.

DESCRIPTION

FIG. 1 is a front view of a ski exercising apparatus; FIG. 2 is a rear view of the ski exercising apparatus; FIG. 3 shows the top view of the ski exercising apparatus; FIG. 4 shows the bottom view of the ski exercising apparatus; FIG. 5 is a left side view of the ski exercising apparatus; FIG. 6 is a right side view of the ski exercising apparatus; and, FIG. 7 is a perspective view of the ski exercising apparatus. The broken line showing of the reinforcing framework of FIG. 4 is for the purpose of illustrating portions of the ski exercising apparatus and forms no part of the claimed design.

1 Claim, 7 Drawing Sheets(56)
